CLAIM

I claim the ornamental design for a gasket, as shown and described.

DESCRIPTION

FIG. 1 is an isometric view of my design for a gasket;

FIG. 2 is a front view of the design for the gasket shown in FIG. 1, the rear view being identical;

FIG. 3 is a left side view of the design for the gasket shown in FIG. 1, the right side view and the top and bottom views being identical;

FIG. 4 is a cross sectional view along line 4—4 of the design for the gasket as shown in FIG. 2;

FIG. 5 is an isometric view of a second embodiment of my design for a gasket;

FIG. 6 is a front view of the design for the gasket shown in FIG. 5, the rear view being identical;

FIG. 7 is a left side view of the design for the gasket shown in FIG. 5, the right side view and the top and bottom views being identical;

FIG. 8 is a cross sectional view along line 8—8 of the design for the gasket as shown in FIG. 6;

FIG. 9 is an isometric view of a third embodiment of my design for a gasket;

FIG. 10 is a front view of the design for the gasket shown in FIG. 9, the rear view being identical;

FIG. 11 is a left side view of the design for the gasket shown in FIG. 9, the right side view and the top and bottom views being identical; and,

FIG. 12 is a cross sectional view along line 12—12 of the design for the gasket as shown in FIG. 10.
